UNITED STATES PATENT OFFICE.

PETER HUBER, OF NEW YORK, N. Y.

FIRE-ESCAPE.

SPECIFICATION forming part of Letters Patent No. 329,648, dated November 3, 1885.

Application filed June 30, 1885. Serial No. 170,247. (No model.)

To all whom it may concern:

Be it known that I, PETER HUBER, of the city, county, and State of New York, have invented certain new and useful Improvements 5 in Fire-Escapes, of which the following is a specification.

This invention relates to fire-escapes of that class in which a sheet, net, or other suitable fabric is supported on a spring-cushioned 10 frame guided on upright standards, so as to receive a person jumping from a window or roof of the building; and the invention consists of a fire-escape formed of upright standards that are connected by folding braces hinged to 15 the fixed collars at the lower parts and to sliding collars at the upper parts of the standards. The upper braces form the supporting-frame for the sheet or net, and are retained in extended position by suitable locking devices. 20 The sheet or net is attached by spiral springs to the upper folding braces and their sliding collars, which latter are supported by strong spiral springs surrounding the standards. A brake device is arranged between the springs 25 of each standard, the brake device serving for conveniently moving the fire-escape and for increasing the friction and resistance of the springs to the falling body.

In the accompanying drawings, Figure 1 30 represents a side elevation of my improved fire-escape; Fig. 2, a plan; Fig. 3, a side view of the same, showing the same in folded position; Fig. 4, a top view of Fig. 3. Figs. 5 and 35 6 are details of the ring-shaped sliding collars of the supporting-standards, and Figs. 7 and 8 are details of the brake device; and Fig 9 is a vertical transverse section on line $x-x$, Fig. 1, drawn on a larger scale, and showing the spring locking device of the braces of the net-supporting frame.

Similar letters of reference indicate corresponding parts.

A, in the drawings, represents four upright standards, which are preferably made of gas- 45 pipe or suitable material. The standards A A are provided with rollers at their lower ends, so as to be readily removed from place to place. The standards A A are connected by folding braces B B and B' B' at their lower 50 and upper ends, the lower braces, B B, being pivoted to fixed collars b b at the lower ends

of the standards A A, and connected by pivots at their centers, while the upper braces, B', are pivoted to sliding collars b' at the upper parts of the standards A, and are supported by strong spiral springs d d, placed around the standards. The upper braces, B', and collars b' form the supporting-frame for the jumping sheet or net C, which is attached at the corners to eyes b² of the collars b', and 55 connected at the sides by short spiral springs a to the folding braces B', as shown in Fig. 2. The ears to which the lower braces, B, are pivoted are closed at their lower parts, while the ears to which the upper braces, B', are 60 pivoted are closed at their upper parts, so as to form a stop for the braces when they are in an extended position. The upper braces, B', are locked together in extended position 65 by spring-pins f, that engage socket-holes of 70 one brace, while the springs f' of the pins are attached to the other brace, as shown clearly in Figs. 1, 2, and 9. In place of the locking-pins, clamping-screws, bolts, or any other equivalent locking device, may be employed 75 for locking the upper braces in extended position.

When the apparatus is desired to be folded up, the locking devices have to be released from the upper braces, B B, upon which the 80 upper and lower braces can be readily folded between the standards, as shown in Fig. 3.

On each standard are preferably arranged two spiral springs, d d, which are separated by means of a sliding collar, e, to the ears of 85 which is fulcrumed an elbow-lever, D, that is provided with a wooden cheek next to the standard A, so as to act as a friction-brake whenever the outer end or handle, D', of the lever D is moved in upward direction. The 90 handle D' serves also for conveniently taking hold of the fire-escape and moving it to the place of use, as required.

The fire-escape is held in position by the handles, which are moved in upward direction 95 at the moment when a person has jumped into the net or sheet, so as to increase thereby the friction with the standards and the resistance to the momentum of the body, whereby the too great lowering of the net is prevented, especially when the person has jumped from a great height. After use the fire-escape is 100

folded up into a small space by releasing the locking devices and folding the braces toward each other, whereby the entire apparatus takes up a comparatively small space, so that it can be readily handled and carried to the place of use.

The fire-escape is intended to be used as a part of the outfit of fire departments, and to be carried on the trucks of fire-ladders to the burning building, so as to be at hand in case of danger.

Having thus described my invention, I claim as new and desire to secure by Letters Patent—

1. The combination of upright supporting-
15 standards having fixed collars at the lower ends and sliding collars at their upper ends, folding braces hinged to said fixed and sliding collars, the upper folding braces being provided with locking devices, a sheet or net attached to eyes of the sliding collars, and by
20 spiral springs to the upper braces, and spiral

cushioning-springs placed around the standards below the sliding collars of the sheet-supporting frame, substantially as set forth.

2. The combination of the upright stand- 25 ards, folding braces hinged respectively to fixed collars at the lower ends and to sliding collars at the upper ends of the standards, the upper braces being provided with locking devices, a sheet or net mounted to the upper 30 movable braces, spiral cushioning-springs placed on the standards, and sliding collars having friction-levers interposed between the springs, substantially as set forth.

In testimony that I claim the foregoing as 35 my invention I have signed my name in presence of two subscribing witnesses.

PETER HUBER.
